Inventor

UNITED STATES PATENT OFFICE.

MARGARET GLOSSOP, OF SEATTLE, WASHINGTON.

ILLUMINATED DOOR-KNOB.

1,263,880.

Specification of Letters Patent. Patented Apr. 23, 1918.

Application filed October 8, 1917. Serial No. 195,468.

To all whom it may concern:

Be it known that I, MARGARET GLOSSOP, citizen of the United States, residing at Seattle, in the county of King and State of Washington, have invented a certain new and useful Improvement in Illuminated Door-Knobs, of which the following is a specification.

My invention relates to improvements in luminous door knobs, and the object of my invention is to provide a door knob which shall embody luminous portions thereby to enable one readily to find said door knob in the darkness of night, said door knob being associated with the latch of a door in such manner that it may be turned by one's hand to actuate said latch in the operation of opening said door.

I accomplish this object by devices illustrated in the accompanying drawings, wherein—

Figure 1 is a view in vertical mid-section on broken line 1, 1 of Fig. 2, showing a door knob embodying my invention;

Fig. 2 is a view in front elevation of the same, certain parts of which are shown with fragments thereof removed; and

Fig. 3 is a cross-sectional view of the same on broken line 3, 3 of Fig. 1.

Referring to the drawings throughout which like reference numerals indicate like parts, in Fig. 1 is shown the rearward portion 4 and the frontward portion 5 which comprise separable metal portions of a hollow door knob.

The rearward portion 4 is provided with an integral cylindrical portion 6 through the central portion of which extends longitudinally a hole, of square cross-section, within which is fitted one end portion of a shaft 7 of a door latch not shown, which shaft 7 is of square cross-section as shown in Fig. 3.

The shaft 7 is fastened in its position within the cylindrical portion 6 in a well known manner by a screw 8.

The circular wall of the rearward portion 4 flares outwardly from the cylindrical portion 6 to terminate in the form of an integral beaded flange 9 whose internal surface is provided with a screw thread that extends from the annular face of said flange 9 to an annular shoulder 10 from the inner edge of which shoulder 10 the internal surface of said portion 4 converges to the inner end of the shaft portion 4 whereby the interior

space of said portion 4 is of the form of a frustum of a cone, as shown in Fig. 1.

For the sake of clearness I have shown the frontward portion 5 as being separated from the rearward portion 4.

The frontward portion 5 is of annular form and is provided with an externally screw threaded flange 11 which is adapted to screw into the internally screw-threaded flange 9, the internal surface of said portion 5 being formed to provide two spaced annular shoulders 12 and 13 against each of which is disposed a circular glass plate like a watch crystal, as glass plates 14 and 15 respectively, which glass plates 14 and 15 are secured in their respective positions by fillets 16 and 17 respectively of putty or other form of cement.

Disposed to be clamped between the shoulder 10 and the annular face of the flange 11 of the portion 5, is the flange 18 of a cup-like member 19 whose wall corresponds in shape to the inner surface of the portion 4 which member serves as a removable lining of said inner surface.

The interior surface of the cup-like member 19 may be coated with a phosphorescent paint that is self luminous to such degree as will cause rays of light to be projected through the glasses 14 and 15, which rays of light will be perceptible in the darkness of night thus to indicate the location of the door knob, or preferably the space between the two glass plates 14 and 15 may be filled with a mass of phosphorescent paste that is sufficiently self luminous to project rays of light through the glass plate 15, thereby to make observable the location of the door knob in spite of surrounding darkness.

In practice it is found that a mass of phosphorescent paste disposed between the glass plates 14 and 15 will retain its luminosity for a longer time than will phosphorescent paint when applied to the inner surface of the cup-like member 19, but said inner surface can be more easily repainted with such phosphorescent paint than can be renewed the phosphorescent paste that is disposed between the glass plates 14 and 15.

If desired, only the outer surface of the inner glass plate 14 may be painted with phosphorescent paint to make the door knob self luminous, or only the inner side of the outer plate 15 may be so painted, but in either of such cases the door knob will re-

main self luminous for shorter period of time.

In case phosphorescent paint is applied to the inner surface of the cup-like member 19 5 to supply luminous rays of light then, in such case, the glass plate 14 may be omitted, such glass 14 being necessary only when a mass of phosphorescent material is to be confined within the space between the two 10 glass plates 14 and 15.

Obviously, changes may be made in the forms, dimensions and arrangement of parts of my invention without departing from the spirit thereof.

15 What I claim is:

1. A door knob of the class described, which embodies two separable portions, the rearward one of which is hollow and provided with a rearwardly extending cylindrical part that has a hole of square cross-section extending therethrough and the circular wall of which rearward one flares outwardly to terminate in an internally screw-threaded flange, and the forward one of 20 which separable portions is of annular form and provided with two spaced annular shoulders on its internal surface and with an externally screw-threaded annular flange 25 which is removably disposed within said internally screw-threaded flange of said rear-

ward portion; two circular glass plates, the circular edge portion of each of which is fastened against a different one of said annular shoulders; and a lining of sheet metal removably disposed against the inner surface of the circular wall of said rearward one of said separable portions. 35

2. A door knob of the class described, which embodies two separable portions, the rearward one of which is hollow and provided with a rearwardly extending cylindrical part that has a hole of square cross-section extending therethrough and the circular wall of which rearward one flares outwardly to terminate in an internally screw-threaded flange, and the forward one of 40 which separable portions is of annular form and provided with two spaced annular shoulders on its internal surface and with an externally screw-threaded annular flange 45 which is removably disposed within said internally screw-threaded flange of said rearward portion; and two circular glass plates, the circular edge portion of each of which is fastened against a different one of 50 said annular shoulders. 55

In witness whereof, I hereunto subscribe my name this 29th day of September, A. D. 1917.

MARGARET GLOSSOP.
